W. V. Peeken

UNITED STATES PATENT OFFICE.

WINFRED MUDGE BROOKS, OF SOUTH ORANGE, NEW JERSEY.

SEALING MEANS.

Application filed April 19, 1921. Serial No. 462,661.

To all whom it may concern:

Be it known that I, WINFRED M. BROOKS, a citizen of the United States, and a resident of South Orange, in the county of Essex and State of New Jersey, have invented certain new and useful Improvements in Sealing Means, of which the following is a specification.

This invention relates generally to sealing means for cords or the like, and has for its main object and feature a sheet material seal simple in construction, effective in sealing and capable of revealing any tampering with the contents of the package to which it may be attached.

In the accompanying drawings the invention is disclosed in several concrete and preferred forms in which—

Fig. 1 is a general view of a package showing the method of attaching the seal of the invention.

Fig. 2 is an enlarged detail view showing the seal bent up and the cord sealed.

Fig. 3 is a sectional view on the plane of line 3—3 of Fig. 2.

Fig. 4 is a perspective detail view showing the seal bent up and broken.

Fig. 5 is a plan view of a blank of sheet material from which the seal is made, showing one form of the invention.

Fig. 6 is a sectional view on the plane of line 6—6 of Fig. 5.

Fig. 7 is a plan view of a blank of sheet material showing a modified form of the invention.

1 indicates a main portion having an aperture 2 adjacent to the opposite sides of which are two upstanding lugs 3 both struck up in the same direction from the face of the main portion. The two cords 4 are threaded through the aperture. As shown in Fig. 7 this may constitute a complete sealing member; and, in that event, a weakened zone 5 preferably extends transversely of the seal in the plane of the aperture and intermediate the lugs. It will be understood that after the cords are passed through the aperture, the seal is bent back upon itself in such direction as to cause the lugs to approach each other thereby clasping the cords between the faces of the members of sheet material and causing the lugs to enter the cords and also to force them sidewise into the aperture for, it will be observed, the lugs 3 terminate short of the ends of the aperture. If it is now attempted to unbend the mem-

ber of sheet material, the weakened zone will fracture the material and thus indicate that the seal has been broken.

In the more elaborate form of the invention shown in Fig. 5, the weakened zone 5 may be retained or may be omitted. In this form of the invention, the main portion is provided with an auxiliary portion 6 and preferably a weakened zone 7 is formed between the main and auxiliary portions. That face of the main portion which is opposite to the one having the projecting lugs is provided with a symbol indicating that the seal has been broken. This symbol may be of any suitable character such as the word "broken" or it may be a dot or any other appropriate indicia. It will now be understood that, with the form of the invention shown in Fig. 5, the bending of the main portion along line 5 will expose the symbol indicating a broken seal but that, by bending back the auxiliary portion upon the doubled-up main portion, this symbol is hidden, as indicated in Fig. 2. If it is now attempted to unbend the auxiliary portion, the metal will fracture along line 7 and the symbol will be exposed, as indicated in Fig. 4. If desired, the auxiliary portion may carry the name of the shipper in the exposed part 85 of that portion. To insure that sufficient bending to fracture the material will occur before the seal can be opened, it is preferred to provide the main portion with a notch 8 at one end and to separate the auxiliary portion from the main portion by means of a relatively narrow neck 9 so that when the seal is bent up, as indicated in Fig. 2, said neck will enter the notch.

It will be seen that, by the means described, a package, as 10, may be tied with cord and a knot 11 formed in the cord. The loose strands, extending from the knot, may then be sealed in the manner described; and, if desired, the seal may be slipped 100 through a shipping tag 12 by slitting the tag slightly to admit of the passage therethrough of the seal.

With the form shown in Fig. 5 and with both weakened zones 5 and 7 used, it will 105 be observed that the auxiliary portion forms an outer seal, as it were, in that the doubled-up main portion still seals the package because the metal of the main portion must be fractured before access may 110 be had to the contents of the package. Thus, if auxiliary portion 6 is broken off,

the device will indicate that the outer seal has been broken and yet retain the package in sealed condition by reason of the inner seal.

5 I claim:

1. Sealing means comprising: a member of sheet material having a main portion, provided with an aperture, for the reception of strands, and an auxiliary portion at one end, said main portion being bent back upon itself along a line extending transversely through the aperture, and said auxiliary portion being bent back upon the doubled-up main portion.

10 15 2. Sealing means comprising: a member of sheet material having a main portion provided with an aperture, for the reception of strands and an auxiliary portion at one end separated from the main portion by a weakened zone, said main portion being bent back upon itself along a line extending transversely through the aperture and parallel to the weakened zone aforesaid, and said auxiliary portion being bent back upon the doubled-up main portion.

20 25 3. Sealing means comprising: a member of sheet material having a main portion, provided with an aperture for the reception of strands, said main portion having further a notch at one end and an auxiliary portion separated by a relatively narrow neck from the main portion at its other end, said main portion being bent back upon itself along a line extending transversely through the aperture, and said auxiliary portion being bent back upon the doubled-up main portion in such direction that the narrow neck enters the notch of the main portion.

30 35 4. Sealing means comprising: a member of sheet material having a main portion, provided with an aperture for the reception of strands and provided, on one of its faces, with a symbol indicating that the seal has been broken, and an auxiliary portion at one end, said main portion being bent back upon

itself along a line extending transversely through the aperture and in such direction as to bring that face carrying the symbol outermost, and said auxiliary portion being bent back upon the doubled-up main portion in such direction as to cover the face carrying the symbol. 50

5. Sealing means for cords or the like comprising: a member of sheet material having an aperture, for the reception of strands, and upturned lugs at opposite sides of said aperture but on the same face of the sheet material member, said member also having an auxiliary portion at one end, said main portion being bent back upon itself along a line extending transversely through the aperture at a point intermediate the lugs, the bend being in such direction as to cause the lugs to approach each other, and said auxiliary portion being bent back upon the doubled-up main portion. 55

6. Sealing means for cords or the like comprising: a member of sheet material having an aperture for the reception of strands, and upturned lugs at opposite sides of said aperture but on the same face of the sheet material member, said member also having a symbol, indicating that the seal has been broken, upon that face which is opposite to the one carrying the lugs, and an auxiliary 70 portion at one end of the main portion, said main portion being bent back upon itself along a line extending transversely through the aperture at a point intermediate the lugs, the bend being in such direction as to cause the lugs to approach each other and to bring the face carrying the symbol outermost, and said auxiliary portion being bent back upon the doubled-up main portion in such direction as to cover the face carrying 75 the symbol. 80

Signed at New York city, in the borough of Manhattan, county and State of New York, this 12th day of April, 1921.

WINFRED MUDGE BROOKS.
